UNITED STATES PATENT OFFICE.

ERNEST L. WOOLLEY, OF PROVIDENCE, RHODE ISLAND.

OIL-BURNER.

1,387,877.

Specification of Letters Patent. Patented Aug. 16, 1921.

Application filed November 10, 1919. Serial No. 338,796.

To all whom it may concern:

Be it known that I, ERNEST L. WOOLLEY, a subject of the King of Great Britain, residing at Providence, in the county of Providence, State of Rhode Island, have invented certain new and useful Improvements in Oil-Burners, of which the following is a specification.

My invention relates to liquid-atomizers 10 and more particularly to oil-burners for atomizing fuel-oil and injecting it into the combustion-chamber of a furnace by mechanical action, without the use of compressed air or steam.

15 One object of my improvement is to provide a simplified form of burner comprising but two parts, which are economical to manufacture and easy to assemble with very little machine work and fitting.

20 Another object of the improvement is to provide a burner which requires no setting or adjustment when once in place.

A still further object of the improvement 25 is to provide a burner which may be easily removed for cleaning and readily assembled again without requiring expert attention.

Various other objects of the improvement 30 will appear from the description of the construction and method of operation of the device as fully set forth in the following specification, illustrated by the accompanying drawings, in which like reference characters designate like parts. In the drawings:

35 Figure 1 is a sectional view taken in a plane coincident with the axis of the burner and illustrating the feed-pipe to which it is attached;

Fig. 2, a plan view of the burner-tip;

40 Fig. 3, a transverse, sectional view of the nozzle of the burner showing the fuel-ducts leading therethrough; and

Fig. 4, an axial, sectional view of the same taken on the line $\alpha-\alpha$ of Fig. 3.

45 Referring first to Fig. 1, 2 designates the main feed-pipe through which the oil or other liquid fuel is delivered from its source, said pipe being usually arranged to project into the combustion-chamber of the furnace and 50 being provided with suitable valves to control the flow of the oil under pressure. At its inner end the pipe 2 is exteriorly threaded to receive a cap 3 which constitutes the tip of the burner. The cap 3 may be of cylindrical shape, but is preferably hexagonal on 55 its sides as shown in Fig. 2, or it may be

part cylindrical and part hexagonal, to provide for its convenient application to, and removal from, the feed-pipe 2 with an ordinary wrench.

In the end of the cap 3 is a central opening 4 having a contracted orifice at 5 formed with conical, flaring walls 6 and 7 diverging at either side. The outer, flaring end 7 of the discharge-opening 4 is illustrated in Fig. 60 1 as being somewhat larger in diameter than that of the inner end 6, the conformation of this delivery end of the tip 3 serving to define the shape of the spray emitted from the burner, and being variable by substituting 65 different types of tips in accordance with different conditions of operation.

Seated within the interior of the cap or tip 3, abutting its end wall and held against the end of the feed-pipe 2, is a cylindrical, 70 disk-like plug 8 which constitutes the spraying-nozzle or atomizer of the burner. The plug 8 is provided with a central, cylindrical recess or oil-chamber 9 which is closed at one end by the wall 10 of the plug, while its 75 opposite, open end is adapted to register with the inner, flared end 6 of the opening 4 in the cap 3. Leading into the oil-chamber 9 are oil-ducts 11 formed by holes drilled through the periphery of the plug 8 tangential with the cylindrical wall of the chamber. Any convenient number of these 80 ducts 11 may be provided, four being the usual number as illustrated in Fig. 3. Communicating with the ducts 11 are lateral 85 inlet-openings 12 drilled through the inner, flat side of the plug 8 at a slight distance from its periphery. When the nozzle or atomizer 8 is assembled within the cap 3, with its end against the feed-pipe 2, the 90 inlet-holes 12 will lie within the bore of the feed-pipe whereby to provide passages for the oil to allow it to be forced through the ducts 11 and thence to the oil-chamber 9.

Having now described the construction 95 and arrangement of the parts of my improved device, its method of operation will next be explained:

The burner is assembled on the feed-pipe 2 by simply setting the nozzle-plug or atomizer 8 against the end of the pipe and screwing the cap 3 onto the threads. As the tip or cap 3 is screwed into place it will force the plug or disk 8 snugly against the end of the pipe 2 and hold it in fixed position with 100 the oil-chamber 9 registering with the inner, conical end 6 of the discharge-opening 4.

The end of the pipe 2 will thus be closed by the plug 8, except for the relatively small holes 12 leading into the ducts 11. When the oil or other liquid fuel is forced through the pipe 2 under pressure it will be caused to flow through the openings 12 into the ducts 11, and thence will be delivered into the chamber 9 in a plurality of streams which spurt tangentially to the cylindrical walls of the chamber. This action causes the oil to be whirled around the chamber 9 with a gyratory motion whereby it is ejected out through the orifice 4 in a fine spray, the fuel being atomized as it is emitted from the cap 3 and spread out into a funnel-like jet, as regulated by the conical wall 7 of the opening 4. By substituting caps of different types, as regards the discharge-opening 7, the angle and spread of the spray may be varied as required.

It will be observed that my improved burner comprises only two essential elements: the nozzle or plug 8 and the tip or cap 3. The nozzle 8 is of extremely simple structure, consisting of a lozenge-shaped disk having an axial hole drilled part way through its flat side, with the smaller oil-duct drill-holes leading thereto. This element of the device may be manufactured at relatively small cost, the disks being produced in quantities from round rod and finished in a lathe after which they may be easily drilled in a drill-press of usual type. The cap or tip 3 is likewise of a structure to render it easy and cheap to manufacture from blanks cut from hexagonal rod or shaped in a screw-machine. Very little machining is necessary for this piece, the operations of drilling and tapping its bore 40 and drilling and counterboring the end orifice being very simple and easily and quickly accomplished by the usual methods employed on screw-machines.

It is to be particularly noted that only one threading or tapping operation is required on the whole burner and, particularly, that there is no finishing and fitting required between its parts. The plug or disk 8 may be left unfinished on its periphery and the bore 50 in the cap 3 made large enough to provide a slight clearance around its sides. The plug will thus fit the cap loosely, but nevertheless it will be held tightly in position against the end of the feed-pipe 2 when the cap is screwed snugly onto the pipe.

It will also be observed that the parts of the burner do not require any setting or adjustment to apply them to use. They may be assembled on the feed-pipe by the ordinary pipe-fitter or other inexpert laborer and when once in place cannot get out of order or become deranged. Likewise, the burner is easy to take apart for cleaning and may be reassembled again with the use 60 of a wrench without danger of damage or

misarrangement of the parts. After the plug or atomizer 8 has been removed it is very easily cleaned with a wire or other pointed instrument. For this purpose the oil ducts in the plug are made straight, 70 without crooks or bends, so that the cleaning tool may be readily inserted through them. The wire or other tool is simply pushed through the holes 11 from the outside to force any obstruction or gummed oil into the 75 central chamber 9, from which it may be readily scraped away; and the lateral holes 12 may also be as easily cleaned by inserting the wire through them.

The burner cap or tip 3, being made from standard or stock blanks, may be manufactured so cheaply that various styles can be furnished at slight expense, the different types varying in the shape of their delivery openings to provide for different spread 85 and angle of the flame produced by the spray. My improved device is thus much more economical in use than the usual type of burners having a more complicated structure and arrangement; and furthermore, its simplicity makes for higher efficiency of operation and greater durability in use.

I am aware that it is old in the art to employ an oil-burner having an atomizer provided with a central chamber with oil ducts leading tangentially thereto. I do not claim this structure broadly, therefore, but only the herein described improvement which consists essentially in making the 100 burner in two parts, and in so designing its elements that they may be manufactured by simple machining operations whereby to reduce the cost; and whereof the parts may be assembled without fitting, finishing or adjustment, while being easily removable for cleaning.

What I claim and wish to secure by Letters Patent is:

1. A two-part oil-burner for attachment 110 to a fuel feed-pipe comprising a cap adapted to be applied to the end of the pipe, said cap formed with a contracted discharge opening at its end, and a disk-like plug fitted within the cap to be held thereby 115 against the end of the pipe, said plug formed with a central cylindrical recess communicating with the contracted discharge opening in the cap, with oil-ducts leading from the periphery of the plug into said central recess, and passages leading from the rearward side of the plug into the oil-ducts 120 to form a connection between the feed-pipe and the central recess of the plug.

2. In an oil-burner for attachment to feed-pipes having threaded ends, the combination with a cap having a threaded bore fitted to the threads on the pipe and a contracted discharge opening provided with conical walls at its opposite sides, of a cylin- 130

drical plug fitted to the bore of the cap to adapt it to be held thereby against the end of the feed-pipe, said plug formed with a central, cylindrical recess registering with 5 the inner conical end of the discharge opening in the cap, and relatively small oil-ducts drilled through the periphery of the plug tangential to the walls of its cylindrical recess with inlet holes drilled 10 through the inner flat side of the plug into the oil-ducts.

3. A fuel oil burner, comprising a barrel adapted to be connected to a fuel supply, a cap secured to the forward end of said barrel 15 and provided with a nozzle opening the inner portion of which forms a rearwardly flaring

conical throat, and an atomizing or disrupting member consisting of a disk interposed between the cap and the front face of the barrel, said disk having a central circular recess in its front face the outer periphery of which is substantially coincident with the periphery of the base of said conical throat, and having ducts or grooves extending tangentially outward from said recess and in 20 the same plane therewith, and passages extending through the disk to connect the outer ends of said ducts with the bore of the barrel.

In testimony whereof I affix my signature. 30

ERNEST L. WOOLLEY.
